UNITED STATES PATENT OFFICE.

JAMES S. BRADFORD, OF BEDFORD, OHIO.

WATER VALVE FOR CONTROLLING FLOW OF GASES.

Application filed May 13, 1919. Serial No. 296,886.

To all whom it may concern:

Be it known that I, JAMES S. BRADFORD, a citizen of the United States, residing at Bedford, in the county of Cuyahoga and State of Ohio, have invented certain new and useful Improvements in Water Valves for Controlling Flow of Gases; and I do hereby declare the following to be a full, clear, and exact description of the invention, such as will enable others skilled in the art to which it appertains to make and use the same.

My invention relates to improvements in valves for controlling the flow of producer gases.

An important object of this invention is to provide means for accurately controlling the flow of gases through the medium of a water valve wherein the height of the water within the valve regulates the flow of gas.

A further object of this invention is to provide a valve of the character described, which is of highly simplified construction, reliable and efficient in use.

A further object of this invention is to provide a water valve having a detachable bottom adapted to be removed for affording access to the interior of the valve for cleaning and repairing purposes.

A further object of this invention is to provide a water valve for gas conduits having a port adapted to permit the firing of the producer gas generator to a gassing state before being cut into the main conduit.

In the accompanying drawing forming a part of this application, and in which like numerals are employed to designate like parts throughout the same,

Figure 1 is a longitudinal vertical section through a water valve embodying my invention and a portion of a conduit, and

Figure 2 is a transverse section taken on line 2—2 of Figure 1.

In the drawing wherein for the purpose of illustration is shown a preferred embodiment of my invention, the numeral 5 designates a gas conduit lined with bricks.

As illustrated in Figure 1 a valve casing 7 is suspended from and in communication with the conduit 5 and is adapted for the reception of a quantity of water 8. A feed pipe 9 is connected to one side of the valve casing 7 and is provided with a manually operated valve 10 adapted for controlling the supply of water or other fluid to the valve. An outlet pipe 11 is secured to a bottom plate 12 of the valve and is adapted

for drainage purposes. A valve 12' is interposed in the outlet pipe 11 and is adapted to control the discharge of water from the valve. The lower part of the valve casing 7 is provided with an outstanding flange 13 to which the plate 12 is secured by bolts 14. To permit of the ready repair of the brick-work and other internal parts of the valve, the bottom 12 may be readily removed.

A water gauge 15 is in communication with the interior of the valve and registers a quantity of fluid within the same. In the event of the water gauge 15 becoming clogged, openings 16 in the side of the valve 70 may be employed for ascertaining the level of the fluid. The openings 16, however, are normally closed by suitable plugs.

As illustrated in Figure 1, a baffle plate 17 is suspended from the top of the conduit 5 and traverses the same and extends down into the valve through terminating at a point spaced upwardly from the bottom of the same. The baffle plate 17 is guarded by brick walls 18. The baffle plate 17 is adapted to direct the gases in their passage through the flue 5 in a downward direction. To control the passage of the gases through the valve, the water level may be adjusted at the desired height thereby controlling the space between the bottom of the baffle wall and the water level. Flanges 19 secured to the sides of the casing and the sides of the baffle wall support the bottom of the bricks.

As illustrated in Figure 2 a port 20 is provided with the entrance through the casing 7 and its brick lining which is normally closed by a plate 21 secured to the casing by bolts 22. The plate 21 may be removed to allow the gas producer to be fired to a gassing state before being cut into the main conduit. The outlet side of the valve is provided with a detachable plate 23 of the same construction as the plate 21.

While I have shown and described the preferred embodiment of my invention, it is understood that I may make such minor changes in arrangement and construction of parts as will remain within the spirit of the invention and what is claimed.

Having thus described my invention, what I claim is:—

A device of the class described consisting of a gas conduit, a casing integral with and depending therefrom, a baffle wall integral with the conduit and depending into the casing substantially mid-way of its ends and

terminating above the base of the casing, a bottom plate for the casing whereby the latter may retain water, bolts to secure said bottom plate to the casing, flange members 5 within the casing above the lower end of the baffle wall connected to the latter on opposite sides thereof and to the casing, a lining of refractory material within the casing and for which said flange members constitute 10 supports, the casing and lining being pro-

vided with an access opening therethrough on each side of the baffle wall, and closure members for said openings.

In testimony whereof I affix my signature in presence of two witnesses.

JAMES S. BRADFORD.
